FIG. -2

MATHANIEL E. LOOMIS Inventor

By Attorney *C. W. Brown*

UNITED STATES PATENT OFFICE

NATHANIEL E. LOOMIS, OF WESTFIELD, NEW JERSEY, ASSIGNOR TO STANDARD OIL DEVELOPMENT COMPANY, A CORPORATION OF DELAWARE

APPARATUS FOR CRACKING REDUCED CRUDES AND THE LIKE

Application filed March 10, 1926. Serial No. 93,597.

This invention relates to improvements in processes and apparatus for the cracking of hydrocarbons into lower boiling products. The invention will be fully understood from the following description, taken in connection with the accompanying drawings, in which

Fig. 1 is a diagrammatic elevation of one suitable form of apparatus, and

Fig. 2 is a plan view of the same.

Referring to the drawings, reference numeral 1 denotes a shell still or equivalent distillation or vapor-separating means, arranged in a furnace setting 2. The still 1 is preferably provided with internal horizontal flues 3, through which hot combustion gases from the furnace pass to a stack, not shown. The still is connected through line 4 with condensing and fractionating equipment, such as a bubble tower 5. This tower has the usual plates 6, receiving pan 7, vapor heat exchanger 8, vapor line 9, and condenser 10.

A condensate draw-off line 11, having a valve 12, conveys a fraction of the type of gas oil from the pan 7 to an accumulator tank 13. A line 14 serves to supply cooling fluid (ordinarily feed stock for the system) to the vapor heat exchanger 8. A by-pass 15 in line 14 and valves 14', 15', are provided for the regulation of the supply of feed stock. Additional preheat may be supplied in an exchanger 8', which receives the gas oil from the pan 7. Suitable by-pass lines are provided leading to exchanger 8', as shown.

A line 16 carries the preheated feed stock to a tar heat exchanger 17 which is supplied with hot tar from the still 1 through line 18, having a valve 19. The feed stock passes through the tar heat exchanger and thence through pipes 20 and 21, in the latter of which a pump 22 is installed, to a cracking coil 23 arranged in a furnace setting 24. Tar is withdrawn from the tar heat exchanger through valved line 25 to storage or other suitable disposition.

The cracking coil discharges through pipe 26 into either or both of two digesting chambers or soaking drums 27 and 28, in accordance with the regulation of valves 29 and 30 in branch lines 31 and 32. While two or

more drums may be operated in series, the parallel arrangement illustrated is preferred. Draw-off pipes 33 and 34 connect drums 27 and 28 respectively to a pipe 35 which discharges into the still 1.

A pressure release valve 36 is provided in pipe 35. The coil and drums are to be operated at relatively high pressure, as is well understood in the art, and the drums should be thermally insulated as by means of a lagging 37, or in some other suitable way.

The present invention is particularly adapted to the treatment of reduced crudes, for reasons which will be fully presented later. The following example, therefore, is based upon the use of such a stock, though it is to be understood that the invention is not limited thereto.

Assuming the system to be in operation, a stream of reduced crude is preheated in the vapor heat exchanger 8 and tar heat exchanger 17 (also in exchanger 8', if desired), and is then passed continuously into the cracking coil 23 at a temperature of around 500° F. In the coil the temperature of the oil is raised to about 850° F., and at this temperature it enters the drum or drums (27 and/or 28). The temperature of the converted product passing from the drums may be 750° F. or thereabout. Vapors and liquid together are passed from the drum or drums into the still through the pipe 35.

The pressure in the coil and drums may be, for example, about 300 to 350 pounds per square inch. This pressure may be reduced through the release valve 36 to substantially atmospheric pressure. The cooling incident to expansion of vapors may lower the temperature of the oil entering the still to about 700° F. The temperatures and pressures referred to above are those generally preferred, but they may be varied. A pressure control valve may be installed in the line 9, for use if it is desired to operate the still 1 and tower 5 under pressure.

In starting the operation, the still 1 is charged with reduced crude and fired to a distillation temperature. Reduced crude is supplied to the cracking coil, which is suitably fired. The effluent from the coil is dis-

charged into the drum or drums, and the cracked product is delivered into the still, in the manner described.

- The cracking coil and soaking drums may be operated under any suitable conditions. Generally, the oil will be passed through the coil at such a velocity that most of any carbon forming therein is swept out into the drums. Conversion takes place in the coil and drums, in a manner well understood in the art; that is, incipient or partial conversion occurs in the coil and further conversion is effected in the drum, by virtue of the contained heat of the oil.
- 15 The heat content of the oil from the drum is not sufficient to vaporize in the still the amount of gas oil required for best results. The proper amount of additional heat is therefore supplied to the still, preferably by 20 passing hot combustion gases through its internal flues 3. This method of heating is preferred, as it in large measure avoids the coking difficulties in the still which might be encountered if it were attempted to apply 25 external heat. However, some external heat may be applied to the still in the installation shown. All the heat may be supplied externally, if adequate precautions are taken to prevent overheating, for example by using 30 muffle furnaces.

The heating of the still connected with the fractionating tower is of special value in connection with the cracking of reduced crudes. I use this term to mean the residuum of high grade or relatively high grade crudes which have been distilled for the removal of gasoline. Without this heating the percentage yield of gasoline from such stock is limited by two factors, namely 35 the quality of the tar produced, and the amount of gas oil that is available for recycling. If the digestion is conducted at such a temperature that the heat content of the digested oil is sufficient to vaporize an 40 adequate amount of gas oil, the carbon sediment content of the residuum or tar will generally be so high as to prevent its use as fuel oil. Conversely, if the digestion is carried out at a temperature low enough to insure good tar, the amount of gas oil vaporized 45 will be insufficient, and the yield of gasoline on recycling will be correspondingly diminished.

In accordance with the present invention, 50 therefore, I supply heat independently to vaporize the desired amount of gas oil. The cracking is regulated to produce the maximum amount of gasoline that may be obtained without causing the tar to produce 55 too much sediment. The maximum amount of sediment is usually 0.25%. Tar containing not more than this amount will meet "Bunker C" specifications for fuel oil. For example, when working with 55% California crude bottoms (reduced crude), with-

out heating the still or chamber connected to the fractionating tower, the usual yields are about 20% gasoline, 10% refined oil, 20% gas oil, and 50% fuel oil capable of passing the standard sediment tests. The coke and 70 gas loss is small and may be neglected for present purposes. The gas oil may be cracked with about 40% conversion to gasoline, making a total gasoline yield of 28%. With the heated still, the same initial amount 75 of gasoline and refined oil may be obtained, but I take off 40% of gas oil, the residuum being reduced to 30%. With a 40% conversion of the gas oil to gasoline, the total gasoline yield is 36%. In general, the still 80 will be operated to produce at least 30% of gas oil.

The gas oil may be mixed with the reduced crude, if desired, and used as a feed stock for the same coil. It is generally preferred, 85 however, to crack the gas oil in a separate operation. The tar from this operation is available for blending with the tar from the reduced crude to produce a desirable fuel oil product.

The advantages of the invention are not necessarily dependent upon specific details of the construction and operation described, and various changes and alternative arrangements may be made within the scope of 90 the appended claim, in which it is my intention to claim all novelty inherent in the invention as broadly as the prior art permits.

This application is a continuation in part of my application Serial No. 45,195, filed 100 July 22, 1925.

I claim:

Apparatus for cracking reduced crude oil comprising a cracking coil, a digesting drum connected to receive oil from the coil, a fractionating device, a chamber connected with said device, internal flues for at least partially heating the chamber, a connection for passing the cracked product directly and without substantial loss of heat from the 110 digesting drum into the chamber, means for separately withdrawing the gas oil fraction from the fractionating device, heat exchange coils in the upper part of the fractionating device, a heat exchanger through which the hot tar from the chamber is passed and means for supplying the reduced crude through said heat exchange coils and heat exchanger to the cracking coil.

NATHANIEL E. LOOMIS. 120
